CLAIM

I claim the ornamental design for a switch base for an anti-vandal switch, as shown and described.

DESCRIPTION

FIG. 1 is a front, left side, top perspective view of a switch base for an anti-vandal switch showing my new design; FIG. 2 is a front elevational view thereof, the rear elevation view being identical;

FIG. 3 is a right side elevational view thereof;

FIG. 4 is a left side elevational view thereof;

FIG. 5 is a top plan view thereof; and,

FIG. 6 is a bottom plan view thereof.

The broken lines define the bounds of the claimed design and form no part thereof.
